UNITED STATES PATENT OFFICE.

HUGH A. BARNARD, OF HOUSTONVILLE, NORTH CAROLINA.

PAPER BAG.

1,133,911.

Specification of Letters Patent, Patented Mar. 30, 1915.

Application filed September 2, 1914. Serial No. 859,858.

To all whom it may concern:

Be it known that I, HUGH A. BARNARD, a citizen of the United States, residing at Houstonville, in the county of Iredell and 5 State of North Carolina, have invented certain new and useful Improvements in Paper Bags; and I do hereby declare the following to be a full, clear, and exact description of the invention, such as will enable others 10 skilled in the art to which it appertains to make and use the same.

This invention relates to paper bags for mercantile purposes and one of the principal objects of the invention is to provide 15 a paper bag having a sealing flap which can be instantly connected to the bag to hold the contents therein without liability of leakage and which will obviate the necessity of binding cord or string. 20 Another object of the invention is to provide a paper bag or sack having means for sealing the same, thus obviating the necessity for the use of binding string or cord and at the same time being easier and 25 quicker to seal than the paper sacks of ordinary construction in present use.

The foregoing and other objects may be attained by means of the construction illustrated in the accompanying drawing, in 30 which,

Figure 1 is a plan view of a blank for making a paper sack in accordance with this invention, Fig. 2 is a side view of the sack folded and the square bottom of the sack 35 folded up against the side of the bag, Fig. 3 is a side view in which the sealing tongue is turned outward to show the adhesive material upon the upper edge of the tongue and the curved opening in the top portion 40 of the body of the bag to prevent sticking, and Fig. 4 is a perspective view of the bag or sack sealed.

Referring to the drawings, the numeral 1 designates the back portion of a square 45 bottom paper bag, said back portion being folded on the lines 2 and the side portions 3 being folded on the line 4 and when the bag is folded flat the sides are folded inward on the line 5. The front flap portions 50 of the bag are designated 6 and 7, the portion 6 having a curved cut away portion 8

at the upper edge thereof and the lower portion of the side being cut away as at 9, while the portion 7 is provided with a sealing tongue 10, which may be separated from 55 the adjacent portion of the bag on the perforated line 11 when required for sealing. The sealing tongue 10 is also cut away at the lower side as shown at 12.

The bottom portion of the bag has a 60 plain lower edge 13 and is folded along the line 14, while the sides of the bag are folded inward on the lines 15, in the usual manner for bags of this construction.

When the bag is folded and opened up to 65 receive the contents the sealing flap 10 is in front of the bag and is provided with an adhesive substance applied to its upper end as shown at a. When the bag is folded the adhesive substance a will lie in the opening 70 formed by the curved recess and will thus prevent sticking of the tongue to the body of the bag.

When the granular or other material is 75 placed in the bag the tongue 10 is detached upon the line 11 and the top of the bag is folded transversely into as many folds as is necessary to lie firmly on top of the contents of the bag and the tongue then is moistened upon the adhesive surface a and connected firmly over the fold at the top and secured to the back of the bag as shown more clearly in Fig. 4.

From the foregoing it will be obvious 85 that a paper bag made in accordance with this invention may be filled to a point near the upper edge and with one or two folds transversely of the upper edge of the bag sealing tongue 10 may be passed over the 90 folds and connected to the bag in a moment thus obviating the necessity of binding cord and at the same time holding the bag closed against leakage.

Various changes may be made in the details of construction without departing 95 from the spirit and scope of the invention as defined in the claims.

What is claimed is:—

A paper bag having a sealing tongue at the front thereof, said sealing tongue having a free edge, and the opposite edge connected to the bag material by a line of de- 100

taching perforations, a portion of the front of the bag being cut away, and the sealing tongue having an adhesive substance applied thereto in line with the cut away portion at the front of the bag, to prevent sticking of the tongue to the bag when the latter is folded.

In testimony whereof I affix my signature in presence of two witnesses.

HUGH A. BARNARD.
